UNITED STATES PATENT OFFICE

155,167

DESIGN FOR A RING

Floyd C. Kerchner, Cincinnati, Ohio

Application April 18, 1949, Serial No. 2,106

Term of patent 14 years

(Cl. D45—4)

To all whom it may concern:

Be it known that I, Floyd C. Kerchner, a citizen of the United States, residing at Cincinnati, in the county of Hamilton and State of Ohio, have invented a new, original, and ornamental Design for a Ring, of which the following is a specification, reference being had to the accompanying drawing, forming part thereof.

Fig. 1 is a front perspective view of a ring showing my new design;

Fig. 2 is an edge elevational view of the ring; and

Fig. 3 is a side elevational view of the ring.

The dominant feature of my design for a finger ring resides in the rope-like element coiled around the ring shank, the free ends of the coil forming a mounting for the stones, as shown.

I claim:

The ornamental design for a ring, as shown and described.

FLOYD C. KERCHNER.
